RAZOR BLADE HOLDER

Hilton S. Stern, Denver, Colo.

Application May 8, 1944, Serial No. 534,617

4 Claims. (Cl. 30—336)

This invention relates to a holder for razor blades and has for its principal object the provision of a neat, inexpensive, highly efficient device for holding a safety razor blade so that the latter may be used for cutting, scraping and other purposes.

Other objects are to provide a construction for a device of this character which will hold both single and double edge blades without requiring bolts, screws, nuts or other attachment devices.

Other objects and advantages reside in the detail construction of the invention, which is designed for simplicity, economy, and efficiency. These will become more apparent from the following description.

In the following detailed description of the invention reference is had to the accompanying drawing which forms a part hereof. The same numerals refer to the same parts in all views of the drawing and throughout the description.

In the drawing:

Fig. 1 illustrates a typical standard type of single edge safety blade adaptable for use in this device.

Fig. 2 illustrates a typical double edge safety razor blade;

Fig. 3 is a perspective view illustrating an adapter member for adapting the double edge blade of Fig. 2 to the uses of this invention;

Fig. 4 illustrates the double edge blade with the adapter in place thereon;

Fig. 5 is a perspective view of the improved holder with a double edge blade in place therein in the concealed position;

Fig. 6 is a similar view illustrating the blade in the projecting position ready for use;

Fig. 7 is an enlarged horizontal section through the holder taken on the line 7—7, Fig. 5; and

Fig. 8 is a similarly enlarged end view of the holder with the blade removed looking in the direction of the arrow 8, in Fig. 5.

A typical single edge safety razor blade is illustrated at 10 provided with the usual backing member 11. A typical double edge blade of the "Gillette" type is illustrated at 12.

The improved holder comprises a sheet metal member bent back upon itself to form a relatively flat U-shaped blade holder 13. The sides of the holder adjacent the joining point and adjacent the free edges are formed relatively close together, allowing just sufficient space for the passage of a razor blade.

The intermediate portions of the sides of the holder are spaced a sufficient distance apart to 55

allow passage of the backing member 11. These spaced apart sides are formed with elongated opposed indentations 14 which divide the interior space into an inner channel 15 and an outer channel 16.

To place the single edge blade of Fig. 1 in the holder in the concealed position is only necessary to slide the blade between the two sides with the backing member 11 in the inner channel 15. To project the blade for use it is withdrawn from the holder and the backing member 11 is slid into the outer channel 16 which causes the edge of the blade to project beyond the holder.

For use with double edge blades an adapter 17 is employed having two side portions 18 adapted to engage opposite sides of the blade. The two side portions 18 are joined by two arc members 19 which pass over the projecting ends of a typical double edge blade as shown in Fig. 4. After the adapter is in place on the blade it can be slid into the holder 13 similarly to the method above described for single blades in both the concealed or projected positions, as shown in Figs. 5 and 6, respectively.

One end of the holder is cut back as shown to allow the blade to be conveniently pushed therefrom. The latter end of the holder is also provided with bent cross stop members 20 which prevent the blade from being forced entirely through the holder.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A razor blade holder comprising: a piece of sheet metal bent back upon itself along a longitudinal fold; opposed side plates depending from said fold, said side plates being relatively close together adjacent said fold and adjacent their free edges to contact the sides of a razor blade and being spaced apart at their intermediate portions to form an open space for the passage of a razor backing member; and a longitudinally-extending, internal ridge on the inner face of each plate dividing said open space into two channels, said channels being so positioned that when the backing member is in one channel the razor blade will project beyond the free edges of said holder and when in the other channel said blade will be concealed by said edges.
2. A razor blade holder comprising: a piece of

sheet metal bent back upon itself along a longitudinal fold; opposed side plates depending from said fold, said side plates being relatively close together adjacent said fold and adjacent their free edges to contact the sides of a razor blade and being spaced apart at their intermediate portions to form an open space for the passage of a razor backing member; and a longitudinally-extending, internal ridge on the inner face of each plate dividing said open space into two channels, said channels being so positioned that when the backing member is in one channel the razor blade will project beyond the free edges of said holder and when in the other channel said blade will be concealed by said edges; said backing member consisting of two side strips and arch members joining the two strips at their extremities to hold said strips against opposite sides of a razor blade.

3. A razor blade holder comprising: a piece of sheet metal bent back upon itself along a longitudinal fold; opposed side plates depending from said fold, said side plates being relatively close together adjacent said fold and adjacent their free edges to contact the sides of a razor blade and being spaced apart at their intermediate portions to form an open space for the passage of a razor backing member; a longitudinally-extending, internal ridge on the inner face of each plate dividing said open space into two channels, said channels being so positioned that

when the backing member is in one channel the razor blade will project beyond the free edges of said holder and when in the other channel said blade will be concealed by said edges; and stop means extending between the plates at one extremity thereof to prevent a razor blade from being forced completely through the holder.

4. A razor blade holder comprising: a piece of sheet metal bent back upon itself along a longitudinal fold; opposed side plates depending from said fold, said side plates being relatively close together adjacent said fold and adjacent their free edges to contact the sides of a razor blade and being spaced apart at their intermediate portions to form an open space for the passage of a razor backing member; a longitudinally-extending, internal ridge on the inner face of each plate dividing said open space into two channels, said channels being so positioned that when the backing member is in one channel the razor blade will project beyond the free edges of said holder and when in the other channel said blade will be concealed by said edges; stop means extending between the plates at one extremity thereof to prevent a razor blade from being forced completely through the holder; said plates being cut back at said latter extremity to allow finger space for forcing a blade from said holder.
